DU PONT RAYON COMPANY, INCORPORATED, OF BUFFALO, NEW YORK, A COR-
PORATION OF DELAWARE.

BUCKET BRAKE.

Application filed January 6, 1926. Serial No. 79,615.

Our invention relates to a novel method of operating a rayon spinning machine and to a device which is employed in connection with the practice of our method. In the 5 type of machine referred to a plurality of boxes or buckets, as they are commonly known, are mounted upon vertical spindles all of which are normally rotating. The buckets are driven from the spindles by 10 means of a suitable friction drive which will, however, permit ready removal of the buckets from the spindles, all of which are driven from a common source of power. These buckets are of considerable weight and 15 rotate at relatively high speed, the purpose of the rotation being to wind up the rayon as it comes from the spinning nozzles into the form of a cake and at the same time impart the necessary twist to the filaments. When 20 the cake is of sufficient size, it is removed from the bucket. The usual method of emptying these buckets has been to stop the entire machine, empty the buckets as rapidly as possible by lifting them off the spindles and turning them up-side-down, and then as rapidly as possible replace the buckets and thread the filaments again through the guides, so that the buckets will continue the operation of twisting and winding the 25 rayon. This method causes a loss of time in shutting down the machine, thereby materially reducing the amount of rayon that each machine can produce.

It is, therefore, the object of our invention 30 to provide a method which will enable removing and emptying individual buckets without the necessity of shutting down the entire machine. This method is made possible by the provision of our novel and 35 improved brake by means of which the rapidly rotating buckets may be lifted, one at a time, from the spindles on which they are mounted.

In the accompanying drawings in which 40 we have shown selected embodiments of our invention:

Figure 1 shows a section of our improved 45 brake along the line 1—1 of Figure 2, together with the bucket and driving mechanism.

Figure 2 is a plan view of our brake.

Figure 3 is a detail, shown in section, of the braking means.

Figure 4 is a sectional view corresponding to Figure 1 and showing another embodiment of our invention. 55

Figure 5 is a plan view of the embodiment shown in Figure 4.

In Figure 2 are shown two plates 1 and 2 which preferably are made of cast aluminum 60 having downwardly projecting angular corner members 3, 4, 5 and 6 cast integral therewith. On the top of the plates 1 and 2 are cast bosses 7 and 8 and bearings 9 and 10. Rods 11 are secured in the bosses 7 and 8 65 and are adapted to slide through the bearings 9 and 10. On the bosses and bearings 7, 8, 9 and 10 are upright ears or extensions 12, 13, 14 and 15, through which extends rods carrying hand grips 16 and 17 by 70 means of which the operator may reciprocate the plate 1 along the rods 11. On the rods 11 are placed springs 18 and 19 received between the bosses 7 and 8 and the bearings 9 and 10 and tending to force the plates 1 75 and 2 apart. The movement of the plates 1 and 2 is limited by means of stops in the form of pins 20 and 21 disposed at the end of the rods 11.

On the interior of the angular corner 80 members 3, 4, 5 and 6 are secured cam blocks 22 by means of bolts 23. The inside surfaces of these blocks are curved to conform to the shape of the rim 35 of a spinning bucket 24, and the blocks are preferably made of aluminum. 85

On the under surface of each of the plates 1 and 2 is secured a brake shoe in the form of a fiber sheet 25 which is held in place by rivets 26. These fiber sheets cover the entire under surface of the plates 1 and 2 90 that come in contact with the rim of the bucket 24.

A bracket 27 is secured to the plate 2 by means of bolts 28 and 29, and is provided 95 with a boss 30 in which a rod 31 is fitted. This rod 31 is provided with a handle 32.

The operation of the device is as follows:

The operator seizes the handle 32 in his left hand and the hand grip rods 16 and 17 100 with his right hand. The springs 18 and 19 tend to keep the plates 1 and 2 in an extended position and the corners 3, 4, 5 and 6 apart so that the device can be slipped down over the rim 35 of the bucket 24. The 105 operator lowers the device over the rapidly

- rotating bucket and, when the lower rim of the blocks 22 is below the rim 35 of the bucket, he presses the grips 16 and 17 together which causes the plates 1 and 2 to 5 move together along the rods 11 and causes the blocks 22 to press against the rim 35 of the rotating bucket. Since the blocks 22 are curved to conform to the contour of the rim of the bucket, they act as cams and, on 10 coming in contact with the rim of the bucket, they tend to lift the bucket so that the top surface of the bucket comes into engagement with the fiber sheets 25. The pressure of the blocks 22 against the edge of the bucket 15 and the fiber sheets 25 against the top of the bucket, due to the pressure exerted by the hand of the operator upon the grips 16 and 17, causes the bucket to cease rotating and at the same time tends to lift it off the driving plate 33 and the spindle 34. The handle 20 32 assists the operator in lifting the bucket 24 and at the same time prevents the device from being twisted from his hands by the force of the rapidly rotating bucket.
- 25 In Figures 4 and 5 we have illustrated another modification of our invention in which we employ a spring to exert the gripping and braking action on the bucket. This embodiment comprises two gripping members 36 and 37 pivotally joined together at 30 38. The members 36 and 37 are provided with handles 39 and 40 respectively, whereby a pivotal movement therebetween may be caused. The members 36 and 37 are arcu- 35 ate shaped at their lower edges to conform with the rim 43 of the bucket 41. These lower edges are lined with shoes 42, preferably of aluminum, to contact with the rim of the bucket.
- 40 It will be noticed that the portions of the members 36 and 37 beneath the rim of the bucket are inclined inwardly so as to form cam surfaces, whereby when the members 36 and 37 come into contact with the rim of 45 a bucket, the rim will be forced upwardly along these inclined cam surfaces and into tight engagement with the frictional bucket lining. The members 36 and 37 are normally urged toward one another by means 50 of a spring 45 anchored to the member 37 at 46 and adjacent its other end bearing against an adjusting member in the form of a screw 47 threaded into a boss 48 on the member 36. This screw 47 may be conveniently held in adjusted position by means 55 of the set screw 49. One of the members 36 and 37 is provided with a rod 50 terminating in a handle 51 and corresponding to the rod 31 and handle 32 in function.
- 60 The operation of this embodiment will now be given:
- The operator grips the handles 39 and 40 in his right hand while holding the handle 51 in his left hand, pressing the handles 39 65 and 40 together so as to stretch the members 36 and 37 apart, and thus permitting the brake to be inserted in position on a bucket, this action taking place against a spring 45. Since the lower edges of the members 36 and 37 have passed over the rim 43 of a bucket, the handles 39 and 40 may be released, and then the spring 45 will bring the members 36 and 37 into tight engagement with the rim. Because of the inclined surfaces of the edges of these members, the 70 rim will ride upwardly along the inclined surfaces and come into contact with the uppermost portion 44 of the brake lining. This results not only in braking the movement of the bucket, but also in lifting it 75 from the driving means such as the plate 33 illustrated in Figure 1.
- It will be noticed that in this embodiment the action is opposite to that in the preferred embodiment in that the action of the 80 spring is employed to bring the brake into engagement with the bucket, whereas in the preferred form the spring is employed to release the brake. In the preferred form the force applied to the brake may be varied by 85 the operator when removing any particular bucket, the force being varied as is found necessary to offset the centrifugal force of the bucket, whereas in the form shown in Figures 4 and 5 the force exerted on a 90 bucket is constant for all buckets.
- In both embodiments we prefer to make the part which comes in contact with the rotating bucket of some material which will rapidly conduct away the heat which is generated between the bucket and the brake. For this purpose we have found that aluminum is very efficient, because of its high coefficient of heat conductivity. At the same time the wear on these parts is greatly decreased by employing a metal such as aluminum rather than the usual brake lining material.
- From the above it will be apparent that we have devised a method and a device for 100 use in practicing that method which will permit the ready removal of a bucket from the spindle without making it necessary to shut down the entire machine. One bucket is removed by itself and the rayon emptied 105 therefrom after which the bucket is replaced on the spindle and the operation is repeated with still another bucket. For example, with a machine operating fifty spindles it 110 has been found that the time necessary to make a complete change according to our invention is about the same as that previously required when the whole machine was shut down during the changing. However, it 115 will be obvious that only one spindle is out of operation at one time; the loss of production when our invention is employed is only approximately one-fiftieth of the time formerly required.
- It will be obvious to those skilled in the 120

art that various changes in size, proportions and design may be made without departing from the spirit of our invention, and, we therefore consider that we are entitled to all such changes as fall within the scope of the appended claims.

We claim:

1. A bucket brake comprising a plurality of relatively movable members, a hand grip associated with said members adapted to effect relative movement of the members by the pressure of the hand, a spring opposing said hand pressure, and braking means adapted to engage a bucket to prevent rotation.
2. A bucket brake comprising a plurality of relatively movable members, hand-operated means adapted to move one of the members in one direction by the pressure of the hand, a spring adapted to move said member in the opposite direction, and braking means adapted to engage the bucket upon the contraction of the movable members.
3. A bucket brake comprising two relatively movable members, bucket gripping means secured to each member, a braking surface on each member, hand-operated means for moving one of the movable members in one direction and a spring adapted to move said movable member in the opposite direction.
4. A bucket brake comprising two relatively movable members, bucket gripping means secured to each member, a braking surface on each member, hand-operated means for moving one of the movable members in one direction and a spring adapted to move said movable member in the opposite direction, and cam surfaces on the gripping means adapted to force the bucket into contact with the braking surface.
5. A bucket brake comprising a number of relatively movable members, bucket gripping means secured to each member, a braking surface secured to each member, a spring adapted to hold the members apart, and a hand grip associated with each member whereby the members may be moved together against the action of the spring.
6. A bucket brake comprising two reciprocating members, a hand grip associated with each member adapted to move the members together by the pressure of the hand, a spring opposing said hand pressure, bucket gripping means on each member, braking means on each member, and a cam surface on each gripping means to force the bucket into contact with the braking means upon the contraction of the movable members.
7. A bucket brake comprising a plurality of bucket gripping means, a braking surface, a spring tending to hold the bucket gripping means apart, a hand-operated means for moving the bucket gripping means into con-

tact with a bucket and for moving the bucket into contact with the braking means.

8. A bucket brake comprising two reciprocating members, a hand grip associated with each member adapted to move the members by pressure of the hand, a spring opposing said hand pressure, braking means on the movable members, cam surfaces on the gripping means whereby the bucket is lifted and forced into engagement with the braking means upon the contraction of the movable members, and a handle to hold the brake against rotation during the braking operation.

9. A bucket brake comprising two reciprocating plates, a plurality of gripping means secured to each plate, a plurality of rods secured to one plate on which the other plates are adapted to slide, springs holding said plates apart, a hand grip on each plate whereby the plates may be moved toward each other by the pressure of the hand, cam surfaces on each gripping means, a braking surface on each movable member, and a handle for holding the brake against rotation during the braking operation.

10. A bucket brake comprising a plurality of relatively movable members, bucket gripping means secured to each member, a braking surface secured to each member, a hand grip on each member, a spring adapted to move the movable members in one direction, cam surfaces on the gripping means, and a handle adapted to steady the brake against rotation during the braking operation.

11. A bucket brake comprising a plurality of bucket braking surfaces, a plurality of bucket gripping means associated with said surfaces, and cam faces associated with said bucket gripping means adapted to bring the braking surfaces into operation upon movement of the bucket gripping means.

12. A bucket brake comprising a plurality of bucket gripping means having cam faces thereon, a braking surface, and means for moving the bucket gripping means towards each other, said movement bringing said cam faces into contact with the bucket and forcing the braking surfaces into braking operation.

13. A bucket brake comprising a plurality of bucket gripping means, hand-operated means adapted to move the bucket gripping means into bucket gripping position, a spring tending to move the bucket gripping means out of bucket gripping position, and a braking surface adapted to be brought into braking position by the movement of the hand.

14. A bucket brake comprising a plurality of bucket gripping means, hand-operated means adapted to move the bucket gripping means into bucket gripping position, a spring tending to move the bucket gripping means out of bucket gripping position, a

braking surface adapted to be brought into
braking position by the movement of the
hand, and a handle adapted to hold the brake
against rotation during the braking opera-
tion.

15. A bucket brake comprising two rela-
tively movable plates, two rods secured to one
of said plates on which the other of said
plates is adapted to slide, springs on said
rod for holding said plates apart, bucket
gripping means on each plate, said bucket
gripping means adapted to engage the rim
of the bucket, braking surfaces on each of
said plates, and a handle on each plate
whereby the plates may be drawn together
along said rods by the manipulation of the
hand.

16. A bucket brake comprising two rela-
tively movable plates, two rods secured to
one of said plates on which the other of said
plates is adapted to slide, springs on said rod
for holding said plates apart, bucket grip-
ping means on each plate, said bucket grip-
ping means adapted to engage the rim of

the bucket, braking surfaces on each of said
plates, a handle on each plate whereby the
plates may be drawn together along said
rods by the manipulation of the hand, and a
second handle on one of the plates whereby
the brake is held against rotation during the
braking operation.

17. In a bucket brake, means permitting
said brake to be placed on a bucket rotated
by a driving means, and means for applying
said brake to said bucket to stop its rotation
and without stopping the driving means.

18. In a bucket brake, means permitting
said brake to be placed on a bucket rotated
by a driving means, means for applying
said brake to said bucket to stop its rotation
and without stopping the driving means,
and means operated by the application of
said brake to disengage said bucket from its
driving means.

In testimony whereof, we have affixed our
signatures to this specification.

FRED G. KRAFT.

ARTHUR E. GUENTHER.
